UNITED STATES PATENT OFFICE.

AUGUST RAHNER, OF CRESTON, IOWA.

BOILER-FURNACE.

No. 807,090.

Specification of Letters Patent.

Patented Dec. 12, 1905.

Application filed June 5, 1905. Serial No. 263,883.

To all whom it may concern:

Be it known that I, AUGUST RAHNER, a citizen of the United States, residing at Creston, in the county of Union and State of Iowa, have invented a new and useful Boiler-Furnace, of which the following is a specification.

This invention relates to boiler-furnaces; and it may be described as an improvement upon the boiler-furnace for which Letters Patent of the United States No. 595,339 were granted to myself on the 14th day of December, 1897.

The present invention relates particularly to the construction of the improved boiler-furnace, of a plurality of units each constituting a water-heater and each of said units being provided with flues or passages for the products of combustion.

The invention further relates to the combination with said units of a fire-box at the lower end and a dome or cap at the upper end, each also constituting a water-heater.

Another object of the invention is to so construct and combine the units of the device as to form or constitute a magazine through which fuel may be fed to the fire-box.

A further object of the invention is to provide for the adjustment of the grate in order that the feed of fuel may be regulated.

The invention further consists in the adaptation to the present invention of the automatic fuel-forcing and grate-operation mechanism substantially shown and claimed in my previous Letters Patent above referred to.

With these and other ends in view, which will readily appear as the nature of the invention is better understood, the same consists in the improved construction and novel arrangement and combination of parts, which will be

hereinafter fully described, and particularly pointed out in the claims.

In the accompanying drawings has been illustrated a simple and preferred form of embodiment of the invention, it being, however, understood that no limitation is necessarily made to the precise structural details therein exhibited, but that the right is reserved to any changes, alterations, and modifications to which recourse may be had within the scope of the invention and without departing from the spirit or sacrificing the efficiency of the same.

In said drawings, Figure 1 is a vertical sectional view of a boiler-furnace constructed in accordance with the principles of the invention. Fig. 2 is a side elevation of a boiler-

furnace the dimensions of which have been reduced by removing several of the units shown in Fig. 1. Fig. 3 is a horizontal sectional view taken on the plane indicated by the line 3 3 in Fig. 2. Fig. 4 is a sectional detail view illustrating one of the grate-supports. Fig. 5 is a perspective detail view of the forked contact member used in connection with the invention.

Corresponding parts in the several figures are indicated throughout by similar characters of reference.

The improved boiler-furnace, constituting the present invention in its simplest form, includes the base 1, a fire-box member 2, a magazine member 3, and a cap member 4.

The base 1, which constitutes the ash-pit, may be of any desired shape; but it has in the drawings been illustrated as consisting of an equilateral box provided with a door 5, through which access may be had to the interior. Upon the side and rear walls of the base within the latter are mounted supporting devices 6, adapted to receive the arms of a spider 7, which constitutes the grate-support, the arms of said spider being converged inwardly and upwardly and provided with a pintle 8, upon which the grate 9 is supported for rotation, said grate being of approximately conical shape, so that the contents of the fire-box, which is supported upon said grate, will have a tendency to work in an outward direction when the grate is shaken or rotated. The supporting members 6 are provided with laterally-extending lugs 10, having vertical slots 11 for the passage of the securing-bolts 12, thus admitting of vertical adjustment of the spider and of the grate supported thereon.

The fire-box member 2, as well as the remaining members of the device, are preferably of circular outline and have been so shown, although it is not to be understood that they are necessarily of this shape. The base 1 is provided with an annular flange 13, affording a seat for the fire-box member 2, and the latter consists of a hollow annular casting of suitable dimensions provided near its lower edge with a water-inlet 14 and near its upper edge with an outlet 15. The interior diameter of the chamber formed by this hollow annular casting is such as to form a fire-box of suitable dimensions.

The member 3, which is supported upon the fire-box 2, also consists of a hollow annular casting, the interior diameter of which, how-

ever, is much smaller than its exterior diameter. This member also has a downward depending conoidal portion 16, which dips or extends into the fire-box, terminating a short distance above the apex of the grate. This dipping or depending portion is also hollow and constitutes a part of the water-space of the member 3, which latter is provided with a water-inlet 17 and a water-outlet 18. The member 3 is also provided with a plurality of flues 19, connecting its upper and lower sides. It is preferred that these flues be disposed equidistantly with relation to each other and that said flues when the member 3 is placed in position upon the fire-box shall be ranged within the inner wall of said fire-box, so that no part of said flues shall be obstructed to the upward passage of products of combustion.

The dome or cap member 4 consists of a hollow annular casting, which is preferably of conoidal shape and of proper dimensions to be supported upon the magazine member or upon an intermediate unit, to be hereinafter described. Said cap member is provided with a feed-opening 20 and with an interiorly-disposed chute 21, connecting said feed-opening with the magazine portion of the furnace in order that fuel may be fed into the latter without dropping into the draft-flues. A door or closure 22 is provided for the feed-opening, and the water-space of the cap member is provided with an inlet 23 and an outlet 24. Said cap member is also provided with a smoke-exit 25, which, like the feed-opening, extends through the water-space, which latter is designated 26.

The members thus far described when placed in proper relation to each other, as in Fig. 2 of the drawings, will constitute a complete furnace structure; but for the purpose of increasing the dimensions and the capacity of the device there may be used in connection therewith any desired number of water-heater units, two such units having been shown in Fig. 1 of the drawings, where each unit is designated 26. Each of said units comprises a hollow annular casting, the inner walls 27 of which are of a diameter corresponding to that of the inner wall 28, constituting the magazine portion of the member 3, with which the said units are placed in alinement. Each of said units is also provided with a plurality of flues 29, disposed in alinement with each other and with the flues 19 of the magazine member 3. Each of said units is finally provided with a water-inlet 30 and an outlet 31. It will be observed that in each of the water-heating members the inlet is disposed near the lower edge and the outlet near the upper edge, said inlets and outlets being also on diametrically opposite sides in order that the most complete circulation may be established. These features, however, may be considered incidental and not entirely essential.

It will be obvious that when the members 1,

2, 3, and 4 only are used the magazine of the furnace will be formed by the interior wall of the member 3 only, but that when one or more of the units 26 are employed the dimensions of the magazine will be increased by the interior walls of such units. The upper end of the magazine, as will be seen in Fig. 1, is provided with a cover or closure 32, having a central aperture 33, through which extends a flexible member 34, supporting a weight or follower 35, adapted to move vertically in the magazine and serving to press downward upon the fuel contained in the latter or to follow the said fuel when, owing to its consumption, the height of the fuel within the magazine is gradually lowered. The cap member 4 supports an apertured top plate 36, through which the flexible member 34 extends, said member being guided over a pulley 37, supported upon said top plate, and over suitable guiding means, as 38, upon an upright 39, mounted adjacent to the furnace. The upright 39 is provided with a bearing 40 for a shaft 41, which extends into the ash-pit, and is provided with a pinion 42, the teeth of which are in mesh with teeth 43 upon the under side of the rotary grate. The flexible member 34 is guided under a pulley 44 upon the outer end of the shaft 41 and finally over a guide-pulley 45 near the upper end of the upright 39, the free end of said flexible member carrying a weight 46, whereby it is kept taut. It is obvious that when the weight or follower descends into the magazine the flexible member 34, engaging the pulley 44, will rotate the shaft 41, thus gradually rotating the grate and freeing the latter from accumulations of ashes and clinkers. When it is desired to replenish the contents of the magazine, the follower may be hoisted, thus lifting the lid 32 out of the way of the feed-opening, and thus enabling fuel to be placed in the magazine, after which the follower and the lid may be readily restored to operative position.

The shaft 41, carrying the pinion 42, whereby the grate is rotated, may be provided with an extended non-circular portion 50, adapted to be engaged by a crank 51, whereby the grate, when desired, may be manually rotated by temporarily disconnecting the flexible member 34 from the pulley 44.

It is preferred to provide in connection with this device an automatic indicator, which shall serve to sound an alarm when the supply of fuel in the magazine is nearly exhausted. To this end there is provided upon the standard or upright 39 a bracket 53, having a contact 54, connected by a conductor 55 with one pole of a storage or other battery 56. 57 is a forked spring-contact arranged adjacent to the contact 54, said spring-contact being bifurcated for the passage of the flexible element 34 and located in such a position that when engaged by the weight 46 in the upward passage of the latter it will engage the con-

tact 54. The contact member 57 is connected by a conductor 58 with the battery 56, the circuit including a magneto-bell 59, which is sounded when the circuit is closed. It will be seen that by this simple device notice will be automatically given when the supply of fuel in the furnace is nearly exhausted, so that it may be replenished in time. This automatic indicating device will be found especially useful when the improved apparatus is used for heating greenhouses and other places where it is important that the temperature be kept uniform at all times.

The operation and advantages of this invention will be readily understood from the foregoing description, taken in connection with the drawings hereto annexed. When a furnace of relatively small capacity is constructed, the consumption of fuel may be regulated by elevating the grate so as to permit only a relatively small portion of fuel to pass from the magazine into the fire-box. When the capacity of the furnace is increased by adding one or more water-heater units, the grate may be lowered, thus permitting fuel to pass more rapidly from the magazine into the fire-box.

The construction of the device is extremely simple, and by simply adding to or subtracting from the number of water-heater units furnaces of a great range of capacity may be erected without change of construction.

The inlets and outlets of the water-heating compartments may, if desired, be connected with a common source of supply and with a common exit; but such constructions are well known and within the skill of the mechanic.

It will be observed that under the construction illustrated and described the magazine is entirely surrounded by a water-space except at the open ends thereof, where it is fed with fuel and where it discharges into the fire-pot. In like manner all the parts of the casing which are actually exposed to heat or flame are backed by water-spaces, so as to render it

impossible for any part of the casing to be 45 burned out when the device is in actual operation, and also utilizing every heat unit for the purpose of heating the water contained in the various compartments.

Having thus described the invention, what 50 is claimed is—

1. In a furnace, the combination with a plurality of superposed water-heater units provided with registering openings coöperating to form a fuel-magazine, and also provided 55 with registering-flues for the passage of products of combustion, of a cap member having an annular water-space and a feed-opening; said cap member being also provided with a chute extending from the feed-opening across 60 the flues or smoke-conductors to the magazine, and with a smoke-exit.

2. In a furnace, a plurality of water-heater members coöperating to form a magazine, a base having a grate supported for rotation beneath said magazine, an upright adjacent to the furnace, a shaft supported for rotation on said upright and having grate-operating means at its inner end and a pulley at its outer end, guide-pulleys upon the upright, a weight moving 70 in the magazine, a flexible member connected with said weight, guided under the pulley upon the grate-operating shaft and provided at its free end with a weight whereby said flexible element is kept taut, and an electric circuit including a sounder, a fixed contact-point upon the upright, and a movable contact adjacent to said fixed contact and disposed in the path of the ascending weight at the free end of the flexible element. 75

In testimony that I claim the foregoing as my own I have hereto affixed my signature in the presence of two witnesses.

AUGUST RAHNER.
